UNITED STATES PATENT OFFICE

JOHN FREI, JR., OF CHICAGO, ILLINOIS

DESIGN FOR A WREATH

Application filed November 20, 1930. Serial No. 37,730. Term of patent 7 years.

To all whom it may concern:

Be it known that I, JOHN FREI, Jr., a citizen of the United States, residing at Chicago, in the county of Cook and State of Illinois, have invented a new, original, and ornamental Design for a Wreath, of which the following is a specification, reference being had to the accompanying drawings, forming a part thereof.

In the drawings:

I claim:

The ornamental design for a wreath as shown.

In witness whereof, I hereunto subscribe my name this 13 day of November, 1930.

JOHN FREI, JR.
